United States Patent Office.

JAMES CURTIS, OF CHICAGO, ILLINOIS.

Letters Patent No. 90,732, dated June 1, 1869.

IMPROVEMENT IN PROJECTILES.

The Schedule referred to in these Letters Patent and making part of the same.

To all whom it may concern:

Be it known that I, JAMES CURTIS, of Chicago, in the county of Cook, and State of Illinois, have invented a new and useful Improvement in Slug-Balls for Fire-Arms; and I do hereby declare that the following is a full, clear, and exact description thereof, which will enable others skilled in the art to make and use the same, reference being had to the accompanying drawings, forming part of this specification.

This invention relates to an improvement in musket-balls, whereby they are rendered more effective, in battle at close quarters, than balls of ordinary construction; and

It consists in forming the ball with two (more or less) longitudinal slots, and with two (more or less) horizontal slots, said slots, or cuts in the ball being sufficiently deep to cause the ball to fly into twelve (more or less) parts or slugs when it leaves the muzzle of the gun, as will be hereinafter more fully described.

In the drawing—

Figure 1 is a longitudinal view of an elongated conical ball, divided by longitudinal and horizontal slots, or cuts, which reach nearly to the core of the ball, only sufficient metal being left to preserve the ball in its proper form in handling, and while in the gun.

Figure 2 is a view of the top of the ball, showing the slots radiating from the centre or core.

Similar letters of reference indicate corresponding parts.

A is the conical ball.

B represents the longitudinal slots, or cuts, which extend inward to near the centre or core.

C represents the transverse slots, or cuts, which likewise extend to near the centre.

It is designed that sufficient metal shall be left to preserve the form of the ball when placed in the gun or in the cartridge-case, but not sufficient to hold the parts together, when propelled by the force of the powder, against the resisting atmosphere.

After leaving the muzzle of the gun, the projectile will fly to pieces, and scatter, doing execution in every direction, thus rendering it a formidable destructive agent at close quarters.

Having thus described my invention,

I claim as new, and desire to secure by Letters Patent—

The slots, or cuts B and C, (more or less in number,) in a musket-ball or elongated conical shot, arranged and formed substantially as and for the purposes described.

The above specification of my invention signed by me, this 7th day of November, 1868.

JAMES CURTIS.

CLARENCE E. BENNETT,
C. E. NESMITH.
